UNITED STATES PATENT OFFICE

ROGER W. GRISWOLD 2D, OF BLACK HALL, CONNECTICUT

AEROPLANE WING.

Application filed October 17, 1929. Serial No. 400,192.

This invention is directed to improving aeroplanes with the purpose of making them more safe, particularly as to the disastrous results arising from stalling, or loss of lift.

5 The lift of an aeroplane, as is well known, is due to the variations of air pressure above and below the wing and this varies with the angle of attack and also as the square of the speed of the plane. Up to a certain point the 10 lifting power increases as the angle of attack is increased, but as this angle is increased a critical point is reached as between the angle of attack and the speed of the plane where the lifting power practically ceases and disappears 15 usually follows this condition when it happens close to the ground. The greater portion of the lifting power of the aeroplane wing is believed to be due to the reduced pressure above the wing, this reduced pressure being included in what is usually called the 20 boundary layer above the wing. This reduced pressure induces a forward, or reverse flow of air around the trailing edge of the wing. In normal flight this reverse flow extends 25 forward but a very slight distance, but as the angle of attack is increased and the speed diminished, this reverse flow moves forward on the wing, the boundary layer thickens and finally reduces the lifting power 30 to a point where the normal flow is completely broken down causing what is usually termed burbling in the boundary layer with resultant loss of lift and complete loss of control and the difficulties attending thereto. It 35 has been proposed to avoid this difficulty by opening passages from the bottom of the wing to the top of the wing to create an auxiliary air flow to neutralize, or prevent this increase in reverse movement and thickening 40 of the boundary layer and to restore the normal air flow over the top surface and to thus avoid the burbling action and the loss of lift. While such passages will accomplish this result they produce an abnormal drag in normal flight. To avoid this, it has been proposed 45 to make the wing in sections and open the sections to produce the passages and to close the sections in normal flight. This leads to many complications in structure and reduces very materially the wing strength, par-

ticularly if a plurality of slots are used for accomplishing the purpose. The complication of structure and consequent increase in weight defeats its practicability. This manner of structure, however, has been utilized 55 when confined to a single slot adjacent to the leading edge of the wing. The present invention is designed to correct in an efficient manner the difficulty as to air flow with the angle of attack above the critical of the normal 60 aerofoil in a comparatively rigid structure as may be found in the ordinary wing.

In carrying out the invention slots are provided from the bottom to the top of the wing, the wing portions to the front and rear of 65 these slots being rigid relatively to each other and as a means of preventing abnormal drag at normal speeds the present invention provides means for closing these slots. Features and details of the invention will appear from 70 the specification and claims.

A preferred embodiment of the invention is illustrated in the accompanying drawing as follows:—

Fig. 1 is a cross section of a wing on the 75 line 1—1 in Fig. 4.

Fig. 2 a similar view with the slots in open position.

Fig. 3 a perspective view of one of the slot closure plates. 80

Fig. 4 a plan view of the plane.

Fig. 5 a detail of the control connections.

1 marks the fuselage, 2 the engine, 3 the propeller, 4 the tail, 5 the horizontal stabilizer, 6 elevators, 7 the rudder, 8 the fin or vertical stabilizer. Wings 9 have the usual ailerons 10. The wings are formed with the usual spars 11, connecting struts 12 and braces 13, and the usual skin 14 over this frame. This invention permits of the use of a conventional 85 frame structure.

The leading edge 15 is preferably movably mounted on the wing structure by means of links 16 pivotally mounted at 17 on the frame, the upper ends of the links being connected 90 at 18 to a projection 19 on the movable leading edge. As this edge swings forward it opens a slot 20 which slot permits of a movement of air through the slot so as to obviate the difficulties encountered when the angle 95 100

of attack is above the critical. The action of such a slot at the leading edge is well known and does, to some extent, correct the difficulty encountered when the angle of attack is brought above the critical point. A series of slots 21 extend from the bottom of the plane to the top of the plane. These slots are arranged one in front of the other and have walls formed of the usual skin material of the plane. The slots are gradually restricted toward the top and are inclined upwardly toward the rear so that the air passing through them rapidly increases in velocity as it passes through the slot and emerges at the upper side of the plane at high velocity. The effect of this is to reduce the pressure at the upper surface of the plane to prevent the forward movement of the return flow around the trailing edge of the plane and to avoid the creation of the burbling action as the angle of attack rises above the critical point of the normal airfoil. This action tends to stabilize the aeroplane and permits the continuance of lifting force at speeds well below those of the normal airfoil and while there is a rearward movement of the center of pressure on the wing this rearward motion in the absence of the burbling action above the wing is really a stabilizer rather than one creating the loss of control incident to stalling in present construction. Closure plates 22 are pivotally mounted at 23 on rods 23a along one edge of the bottoms of the slots. The rods 23a are mounted in the frame. These closure plates when in closed position, as shown in Fig. 1, present a lower surface similar to the lower surface of the normal plane and, therefore, create practically no drag in normal flight. The upper ends of the slots are so restricted and so inclined as to present practically no drag in normal flight, particularly as they lead into the boundary layer.

Links 24 lead from the closure plates and are connected with links 25. The links 25 are pivotally mounted at 26 on brackets 26a arranged in the frame. The links 24 and 25

are pivotally connected at 27a to control rods 27 extending forward and aft of the wing, the forward ends of the links 27 being pivotally connected at 28 to links 16. Preferably there is one of the link systems including the links 24, 25 and control rod 27 at each compression strut of the frame of the wing. The leading edge 15 will open automatically and if of sufficient power will open and close the closure plates. I prefer, however to provide in addition to such automatic control a manual control for this purpose. Bell cranks 29 are pivotally mounted on the frame at points 30, one for each of the control rods 27, with push and pull rods 31 leading by connections to the cock pit. Arms 32 of these bell cranks are connected by links 33 with the arms 19 so that as the push and pull rods 31 are moved the leading edge and the closure plates are actuated. The push and pull rods 31 extend to both sides of the plane and the bell crank levers 29 are so arranged that all the slots are opened, or closed simultaneously. It will be noted that the links 24 and 25 are brought into alignment as the plates 22 are closed, thus securely locking them in closed position without further strain on the rod 27.

What I claim as new is:—

1. An aeroplane wing having a movable leading edge and provided with slots extending through the wing from top to bottom with the portions to the front and rear of the slot relatively rigid; closures for said slots; and a connection between the closure and the movable leading edge opening said slots as the leading edge is moved forward on the wing.

2. An aeroplane wing having a movable leading edge and having a slot extending through the wing from top to bottom with the portions to the front and rear of the slot relatively rigid; a closure for said slot; and a connection between the closure and the movable leading edge opening said slot as the leading edge is moved forward on the wing.
